[57] CLAIM

The ornamental design for an electric scooter, as shown and described.

DESCRIPTION

FIG. 1 is a left front perspective of an electric scooter, showing my new design;

FIG. 2 is a view as in FIG. 1, but showing an alternative configuration the invention can assume, with the pivoted steering post in a lower, stowed position;

FIG. 3 is a front elevational view, thereof;

FIG. 4 is an elevational view of one side, thereof;

FIG. 5 is a rear elevational view, thereof;

FIG. 6 is an elevational view of the other side, thereof;

FIG. 7 is a top plan view, thereof; and,

FIG. 8 is a bottom plan view, thereof.
